CONTROL MECHANISM FOR ADJUSTABLE SEATS

Le Grand S. Whedon, Medina, N. Y.

Application July 27, 1936, Serial No. 92,737

10 Claims. (Cl. 155—14)

This invention relates to an adjustable seat installation for vehicles, or other structures, and it has particular relation to an improved supporting and operating mechanism for a seat installation wherein seat supporting members, including the seat bottom can be relatively moved to conform readily to various positions desired by persons of various heights, weights, or other physical characteristics or preferences that might require either average or special seating arrangements.

The improved adjusting and supporting mechanism to which the invention is directed involves improvements over the type of seat installation wherein an occupant while seated can adjust the elements of the seat supporting structure to provide bodily movement of the seat in upward or downward swinging movements, and further the invention provides for substantially direct forward and rearward adjustment with respect to the changing or horizontal position of the seat.

One of the principal features of the invention is exemplified in an arrangement of channel-like guides for receiving slides at each side of the seat structure to obviate tendencies of binding among the parts, and the correlation of this arrangement with adjusting mechanism for controlling a plurality of phases of adjustment of the structure.

The invention is also concerned with an improved adjusting mechanism wherein a unit serves for adjusting more than one feature of the structure in a plurality of phases of adjustment.

In the drawing:

Fig. 1 is a side elevation of a seat supporting and adjusting installation constructed according to the invention:

Fig. 2 is a partial side elevation, on a larger scale, from the side of the structure opposite that shown in Fig. 1, and with portions broken away and shown in section;

Fig. 3 is a partial elevation, on a larger scale, and illustrating the inner side of seat supporting and adjusting mechanism, an intermediate portion of the structure being shown in section.

Fig. 4 is a cross-section, on a larger scale, taken substantially along the line IV—IV of Fig. 2, with the cross-section position shown according to the broken line position of Fig. 2;

Fig. 5 is a cross-section, on a larger scale, taken substantially along the line V—V of Fig. 3; and

Fig. 6 is a side elevation of an alternate form of latching device for the structure.

In practicing the invention a seat structure 10

is installed upon a suitable base 12 which can be in the form of a vehicle floor, or the like, and is provided at each side with a pivotal support 13 connected to an upwardly opening lower channel frame member 14. Each of these members 14 has a rear downward extension 16 resting upon the base 12 and the entire seat structure can be tilted forwardly about the pivotal connections 13.

Front and rear links 20 and 22 of channel form at each side of the seat structure have pivotal connections 23, such as bolts or pins, securing them to the lower rear portion of the frame members 14 and have upper pivotal connections 25 securing them between the sides of downwardly opening channels 26. A rigid brace 27 rigidly connecting the rear links 22 has its opposite end portions extending through one channel side 28 of the link and abuts the adjacent side 29 of this link. The brace is rigidly secured to the link sides by welding, or the like.

One end of a tension spring 30 is provided with an end hook 32 which is connected about a pin 33 anchored transversely in the sides 28 and 29 of one of the rear links 22 adjacent the upper end of the latter. Sleeves or washers 35 are disposed about the pin 33 and the hook is centered between them at an intermediate portion of the pin.

The other end of the spring 30 is also provided with a hook 36 which is mounted about one of the lower front pivotal connections 23 which is in the form of a pin, and an adjacent web portion of the front channel link 20 is formed with a slot 37 to facilitate the mounting of the spring end about the pin 23. The spring 30 is normally under tension and resists movement of the links from the full line position to the broken line position illustrated in Fig. 2; that is, the spring constantly urges the links toward an upright position. It will be observed that the spring 30 is substantially enclosed by the opposed upper and lower channels adjacent one side of the structure and in the lower position of the upper channels 26 (Figs. 2 and 4).

The inner side of each upper channel 26 is provided with a recess 40 into which the transverse brace partially enters to permit unobstructed movement of the links to their lower positions, and a similar notch 41 in one of the lower channel members 14 permits proper movement of other structure to be described.

Sliding channels 42 at opposite sides of the seat structure open downwardly and partially embrace the sides of channels 26. Portions of the sides of the channels 42 are partially cut

away or narrowed, as indicated at 45, to provide for free sliding action of the channels 42 upon the channels 26 within predetermined limits, and to provide stops 47 which limit the sliding movement by engagement thereof with the upper pivotal connections 25. Lower portions of the sliding channels 42 also are provided with inwardly turned flanges 50 which underlap the lower edges of the channels 26 to prevent separation of these channels. However, there is sufficient channel side for slidable engagement from end to end of each sliding channel 42 with the sides of the channels 26.

An adjusting link 60 is pivotally secured at its lower end by means of the pivotal connection 28 that carries one of the rear links upon the lower supporting channel frame 14 at one side of the seat structure, and the upper end of the adjusting link is secured by means of a pivot pin 62 in a downwardly opening channel slide 63 which is slidable longitudinally in the upper channel 26 between the pivotal connections 25, and is maintained against downward displacement by means of inwardly turned flanges 64 formed upon the lower side portions of the channel 26. These flanges 64 are similar in formation and function to the flanges 50. (Figs. 4 and 5).

An inner channel side 65 contiguous with a side 66 of the channel slide 63 has a notch or slot 67 cut therein through its lower edge and the channel slide 63 has a series of notches or slots 68 formed in its lower edge, any one of which is registerable with the notch 67, depending upon the position of the slide as it is moved longitudinally 35 in the channel.

A locking device 70 including a lever 72 is rotatably mounted intermediately in the downwardly extending sides of the channel 26, and the inner end of a horizontal portion 73 of the lever 40 has a head 75 rigidly mounted thereon. Ears 74 on the horizontal shaft portion 73 adjacent the outer side of the channel 26 prevents outward shifting of the lever in the channel sides.

A lug 76 extending rigidly and radially of the head 75 is disposed between a pair of lugs 77 and 78 formed rigidly upon inner end portions of latches 79 and 80 that are rotatably mounted upon the horizontal lever portion 73 between the inner side of the channel and the head 75. End portions 82 and 83 of the latches adjacent the lug 77 and 78, respectively, are spaced on opposite sides of the group of lugs, 76, 77, and 78, and it should be understood that all of these lugs and end portions are spaced from the axis of the 55 horizontal shaft portion 73. Opposite end portions of a tension spring 85 are secured, as indicated at 86 and 87, to the latch end portions 82 and 83, respectively, and the spring which is normally under tension, constantly tends to pivot the 60 latches in opposite directions, or, as viewed in Fig. 3, the outer ends of the latches are constantly urged upwardly.

An angular finger 88 formed rigidly upon the outer end of the latch 79 is movable in the notch 67 and into a registering notch 68 to lock the adjusting slide 63 in various positions in the channel 26, whereby the links 20, 22, together with the channels can be locked in various positions between the full line position and the broken line position of the structure shown in Fig. 3. By rocking the lever 72 in a counter clockwise direction, as viewed in Fig. 3, the lug 76 engages the lug 77 and pivots the latch to withdraw the finger 88 from the notches. Upon releasing the lever 72 the spring 85 forces the latch in the oppo-

site direction into locking relation with the notches.

The outer end of the other latch 80 is provided with a locking finger 90 which is disposed in a notch or slot 92 formed in the inner side of the channel 26 and is movable therein to engage in any of a series of notches 93 formed in the lower edge of the inner side of the downwardly opening sliding channel 42 which partially embraces the upper channel 26 adjacent the side of the seat structure.

By rocking the lever 72 in a clockwise direction (Fig. 3) the lug 76 strikes the lug 77 and pivots the latch 80 to withdraw the finger 90 from the registering notches 92 and 93. As soon as the lever is released the spring 85 pivots the latch into engaging position with these notches. Each latch 79, 80 is independently pivotable. As the lug 76 moves the lug 77 to pivot the latch 79, the lug 83 remains stationary and the tension of the 20 spring 85 is increased to urge the finger 90 more firmly into its locking relation. In the same manner, the lug 77 remains stationary while the lug 76 moves the lug 78.

It will be noted that the portion of the downwardly extending side of the channel 42 in which the notches are formed has its lower edge terminating short of the upper ends of the notches 67 and 68, in order that there can be no possibility of the finger 90 accidentally engaging in any of the notches 93, and in the lower position of the upper channel member 26, the finger 90 has space for proper downward manipulation by virtue of the notch 41.

The upper opposite end portions of the sliding channels 42 are provided with outwardly stamped recessed bosses 95 through which fastening devices 96, such as screws or bolts, are rigidly secured to the seat bottom frame 97 to complete the assembly of the seat installation.

Referring to the modification shown in Fig. 6, the lever 72 is provided with a resilient locking strip 100 rigidly secured thereto, as indicated at 102, and is provided with a plurality of substantially parallel portions 103 connected by reversing curved portions 105. Opposite end portions of the strip spring are provided with locking fingers 106 and 107, corresponding to the fingers 88 and 90, and are adapted to engage in the notches 67, 68 and 92, 93 in substantially the same relation. When the lever is rocked in a clockwise direction the finger 106 is urged more firmly into locking engagement and the finger 107 is withdrawn from locking engagement. The resiliency of the strip permits distortion of one end portion thereof while the other end portion is being withdrawn from the notches and upon release of the lever the withdrawn finger under influence of spring resiliency is immediately and automatically forced back into locking engagement.

Thus as the links 20, 22 are pivoted between their limits of movement they can be locked by locking the adjustable slide 63 in various positions in the manner described. Likewise, the forward and rearward adjustment of the seat bottom upon the channels 26, 42 can be accomplished by releasing the finger 90 and sliding the channels 42 together with the seat carried thereon, to the position desired before again releasing the lever to lock them.

Although only illustrative structure has been specifically shown and described it will be apparent to those skilled in the art that the invention is not so limited but that various changes

can be made therein without departing from the spirit of the invention or from the scope of the appended claims.

I claim:

5. In a seat structure, a frame, a movable mechanism supporting the frame and being movable therewith, a support upon which the mechanism is mounted for movement, a seat bottom carried upon the frame and being movable with 5
10 respect thereto, an adjusting device having first means adjustably connecting said device to the movable mechanism and having second means adjustably connecting said device to the seat bottom, and a single actuating means having 10
15 connections with both of said first and second means and being selectively operable to determine either the adjusted position of the seat bottom with respect to said frame or the adjusted position of said movable mechanism. 15
20 2. In a seat structure, a frame, a movable mechanism supporting the frame and being movable therewith, a support upon which the mechanism is mounted for movement, a seat bottom carried upon the frame and being movable with 20
25 respect thereto, an adjusting member pivotally connected to said frame, and a pair of latches pivotally connected upon said adjusting member, the latches and the adjusting member having means limiting relative pivotal movement of each 25
30 latch in one direction, one of said latches having means selectively engageable with the movable mechanism for varying the relative position of said mechanism and frame, the other of said latches having means selectively engageable with 30
35 said seat bottom for varying the relative position of said seat bottom and frame. 35
3. In a seat structure, a frame, a movable mechanism supporting the frame and being movable therewith, a support upon which the mechanism 40
40 is mounted for movement, a seat bottom carried upon the frame and being movable with respect thereto, an adjusting member pivotally connected to said frame, a pair of latches pivotally connected upon said adjusting member, the latches 40
45 and the adjusting member having means limiting relative pivotal movement of each latch in one direction, one of said latches having means selectively engageable with the movable mechanism for varying the relative position of said 45
50 mechanism and frame, the other of said latches having means selectively engageable with said seat bottom for varying the relative position of said seat bottom and frame, and resilient means connected to said latches and normally urging them into latching engagement with said seat 50
55 bottom and mechanism. 55
4. In a seat structure, a frame, a movable mechanism supporting the frame and being movable therewith, a support upon which said mechanism 60
60 is mounted for movement, a seat bottom carried upon the frame and being movable with respect thereto, an adjusting member pivotally connected to said frame, a pair of latches pivotally mounted intermediate their ends upon said adjusting member, a stop upon said adjusting member disposed between portions of the latches, and a resilient member connected adjacent one end of each latch and normally urging portions of each latch toward said stop, one of said latches 60
65 having means selectively engageable with the movable mechanism for varying the relative position of said mechanism and frame, the other of said latches having means selectively engageable with said seat bottom for varying the relative position of said seat bottom and frame. 65
70 75 5. In a seat structure, a frame, a movable mechanism supporting the frame and being movable therewith, said frame including channel members, a support upon which said mechanism is mounted for movement, a seat bottom carried upon the frame and being movable with respect thereto, said seat bottom including channel slides interfitting in telescoping relation with said channel members, said movable mechanism and one of said channel members including means having registerable openings, an adjusting member pivotally mounted upon one of said channel members, a pair of latches pivotally connected upon said adjusting member, the latches and adjusting member having means limiting relative pivotal movement of each latch in one direction, one of said latches having means selectively engageable with said registerable openings for varying the relative position of said mechanism and frame, the other of said latches having means selectively engageable with said seat bottom for varying the relative position of said seat bottom and frame. 75
8. In a seat structure, a frame, a movable mechanism supporting the frame and being mov-

able therewith, said frame including downwardly opening channel members, a support upon which said mechanism is mounted for movement, a seat bottom carried upon the frame and being movable with respect thereto, said seat bottom including channel slides interfitting in telescoping relation with said channel members, said mechanism including upwardly opening channel members parallel to and facing the downwardly opening channel members, said mechanism further including parallel links pivotally connected to and spacing the upper and lower channel members in various positions of movement in parallelism, a resilient member connected at one end in the upper channel member and at the other end in the lower channel member and normally urging the links toward an upright position, whereby upon movement of the channel members toward each other the resilient member is substantially housed in the channel members to which it is connected, an adjusting device having first means adjustably connecting said device to the movable mechanism and having a second means adjustably connecting said device to said seat bottom, and a single actuating means having connections with both of said first and second means and being selectively operable to determine either the adjusted position of the seat bottom with respect to said frame or the adjusted position of said movable mechanism.

9. In a seat structure, a frame, movable mechanism supporting the frame and being movable therewith, a support upon which the mechanism is mounted for movement, a seat bottom carried upon the frame and being movable with respect thereto, an adjusting member pivotally connected to said frame, a pair of projecting resilient members connected rigidly to said adjusting member, one of said resilient members having means selectively engageable with the movable mechanism for varying the relative position of said mechanism and frame and being responsive to pivotal movement of the adjusting member in one direction for disengaging said one resilient member from the movable mechanism, the other of said resilient members having means selectively engageable with said seat

bottom for varying the relative position of said seat bottom and frame and being responsive to pivotal movement of the adjusting member in the other direction for disengaging said other resilient member from the seat bottom while said one resilient member is urged more firmly into engagement with said mechanism.

10. In a seat structure, a frame having frame members extending adjacent opposite sides of the seat structure, a plurality of substantially parallel links pivotally connected to the frame members adjacent opposite sides of the frame structure, supporting means for pivotally supporting the links and, through the links, supporting the frame, said links being movable in parallelism from substantially horizontal positions to substantially vertical positions, resilient means connected to one of the links and to said supporting means and constantly exerting force tending to move the links toward a vertical position, an adjusting member pivotally connected to the supporting means and slidably engaging the frame, guiding means in the frame for slidably receiving a portion of the adjusting member, a seat bottom having parallel guides slidably supporting the seat bottom upon the frame adjacent opposite sides of the seat structure, said frame and adjusting member having a plurality of recesses registerable in response to relative sliding movement between the frame and adjusting member, said frame and one of said parallel guides having a plurality of recesses registerable in response to relative sliding movement between the frame and the latter parallel guide, a locking device mounted on said frame and having a first locking member selectively engageable with registerable recesses of the frame and adjusting member to lock them in any of a plurality of positions, said locking device having a second locking member selectively engageable with registerable recesses of the frame and said latter parallel guide to lock them in any of a plurality of relative positions, and an actuating member in said locking device selectively operable to actuate said first and second locking members.

LE GRAND S. WHEDON.
